UNITED STATES PATENT OFFICE.

ERNEST B. POETER AND EDWARD POETER, OF IRVINGTON, NEW JERSEY.

DESIGN FOR A HAND-BAG FRAME.

Application filed June 9, 1926. Serial No. 17,999. Term of patent 3½ years.

To all whom it may concern:

Be it known that we, ERNEST B. POETER and EDWARD POETER, both citizens of the United States, residing at Irvington, in the county of Essex and State of New Jersey, have invented a new, original, and ornamental Design for Hand-Bag Frames, of which the following is a specification, reference being had to the accompanying drawing, forming part thereof.

Referring to the drawings, Figure 1 is a side view showing the design of the hand bag frame; Figure 2 is a top view of same; Figure 3 is an end view of same.

We claim:

The ornamental design for a hand-bag frame as shown.

ERNEST B. POETER.
EDWARD POETER.
